THOMAS FITZSIMONS, INVENTOR

BY *Victor J. Adams*

ATTORNEY

UNITED STATES PATENT OFFICE.

THOMAS FITZSIMONS, OF OIL CITY, PENNSYLVANIA.

PUZZLE GAME.

Application filed October 17, 1924. Serial No. 744,241.

To all whom it may concern:

Be it known that I, THOMAS FITZSIMONS, a citizen of the United States, residing at Oil City, in the county of Venango and State of Pennsylvania, have invented new and useful Improvements in Puzzle Games, of which the following is a specification.

This invention relates to game devices, and more particularly to what I term a 10 puzzle game.

One of the main objects of the invention is to provide a game which can apparently be played in a great number of ways but can be won by playing in either one of two 15 ways only. A further object is to provide a game which, as its name indicates, is in the nature of a puzzle, the one who succeeds in solving the puzzle and placing the game pieces on all of the spaces in accordance 20 with the rules of the game being considered as having won the game. Another object is to provide a game of this character which is both interesting and attractive and which will serve to provide mental recreation in 25 playing it. Further objects will appear from the detail description.

In the drawings:—

Figure 1 is a plan view of the game board;

Figure 2 is a plan view of one of the game 30 pieces.

The game board 1 may be of any suitable shape and size and is marked to provide a central circular portion 1^a. Within portion 1^a I provide a series of circularly arranged spaces 2 which are equally spaced and are disposed radially of portion 1^a. I further provide an inner series of spaces 3 which are disposed concentrically with 35 outer spaces 2. Certain of the spaces 3 are connected by lines 4 disposed radially of portion 1^a to the corresponding spaces 2 of the outer series, lines 4 serving as guide 40 lines along which the game pieces are moved, these lines being termed for convenience in description "moving" lines. The remaining outer spaces 2 are connected by moving 45 lines 5 which are disposed diametrically of portion 1^a, these lines connecting the oppositely disposed spaces of the outer series. One of the outer spaces 2 is connected by a moving line 4^a to and adjacent inner space 3, this line extending from an outer space 2 at one end of one of the diametrical mov-

ing lines 5. The inner spaces 3 are connected by moving lines 6 each of which lines connects two oppositely disposed inner spaces 3, certain of these lines being disposed at right angles to the other lines 6.

There are twenty-four moving spaces provided and for convenience in description these spaces are numbered, though this is not essential. The game pieces may also be numbered to correspond to the spaces on the board, if desired, though it is not essential that they be so marked. The object of the game is to place all of the game pieces, of which there are twenty-four, on the spaces of the board without moving over the same moving line or into any of the 70 spaces more than once. It is also a rule that no game piece or button can be removed from a space after it has once been placed thereon. In playing the game the player can start playing from or on any 75 space preferred though there are but two ways in which the game can be played so as to place all of the pieces on the various spaces and conform to the rules above set forth.

One way to play the game and win it is as follows:—start at space 14 and move along line 4 to 13; move from 24 to 14— 80 from 24 to 4—from 10 to 24—10 to 23—3 to 10—3 to 2—17 to 3—17 to 6—12 to 11—21 to 22—21 to 17—12 to 21—9 to 12—9 to 16—8 to 9. The plays thus far made have been made in accordance with the rules above set forth and all of the spaces have 85 been covered except those spaces which are connected by the diametrically extending lines 5. These spaces are readily covered by moving the game pieces from the center space 7 along the lines 6 to the respective spaces to which these lines extend. In this 90 manner the game can be played in accordance with the rules and all of the spaces can be covered. The only other way to play the game to win it in accordance with the rules is by moving as follows:—start at 100 space 12 and move along line 4 to 11; move from 21 to 22—21 to 12—17 to 21—17 to 6—3 to 17—3 to 2—10 to 3—10 to 23—24 to 10—24 to 4—14 to 13—14 to 24—9 to 14—9 to 16—8 to 9. This covers all of the 105 spaces with the exception of those spaces of the outer series to which extend the diametric lines 5, which spaces may be readily

covered by moving the game pieces or discs from the center space 7 along the lines 5 to the respective spaces.

This provides a game which is both instructive and interesting and which requires careful study by any one not familiar with the method of playing the game to win it, as there are so many possible ways of playing the game pieces. As indicated by the conventional shading of the game board, the board is preferably, though not necessarily, provided with portions of various shades and colors to produce a neat and attractive color design, though any suitable design or color scheme may be employed for this purpose.

An additional rule to be observed in playing the game, is that the player is not permitted to move from the space marked "9" to more than one of the inner spaces. In example, the player is permitted to move from space "9" to either of the spaces "14" or "12," but not to both of these spaces. This

rule is intended to make the game harder to solve and correspondingly more interesting to play.

What I claim is:—

In a game of the character described, a game board marked to provide an inner series of circularly arranged spaces for reception of game pieces, an outer series of spaces concentric with said inner spaces, radial moving lines connecting certain of the spaces of the outer series with the spaces of the inner series, moving lines extending diametrically of the board and connecting the oppositely disposed spaces of the remaining spaces of the outer series, a moving line connecting one of said remaining spaces of the outer series with an adjacent space of the inner series, and moving lines connecting the oppositely disposed spaces of said inner series of spaces.

In testimony whereof I affix my signature.

THOMAS FITZSIMONS.
